Attorney

UNITED STATES PATENT OFFICE.

FREDERICK E. MEEHAN, OF PHILADELPHIA, PENNSYLVANIA.

IMPRESSION-LATCH FOR PRINTING-PRESSES.

No. 804,075.

Specification of Letters Patent. Patented Nov. 17, 1908.

Application filed January 19, 1907. Serial No. 353,928.

To all whom it may concern:

Be it known that I, FREDERICK E. MEEHAN, a citizen of the United States, residing at Philadelphia, in the county of Philadelphia and State of Pennsylvania, have invented certain new and useful Improvements in Impression-Latches for Printing-Presses, of which the following is a specification.

My invention relates to improvements in printing presses of the type known as platen or embossing presses.

My invention more particularly relates to the apparatus for operating the impression latches for locking the adjuster-bar by which, through the medium of eccentrics, the pressure exerted by the platen may be regulated.

The press is originally built with a handle for operating the platen, and the apparatus for operating the latches is applied as an attachment. As the latter apparatus is provided with a handle the original handle built with the press must be removed and discarded.

The object of my invention is to construct the levers forming part of the said attachment for operating the latches so that the original handle may be utilized and readily attached to the said levers, thereby greatly reducing the cost of the construction of the attachment for operating the latch levers.

Referring to the drawings: Figure 1. is a side elevation of a portion of a press showing my invention embodied therein; Fig. 2. is a plan view of the apparatus for operating the latches, detached and drawn on a larger scale; Fig. 3. is a front elevation of Fig. 2; Fig. 4. is a vertical section as on line 4-4 Fig. 3.

In the drawings 1 represents a portion of the frame of a printing press, 2 the usual form of platen which oscillates on guides formed for that purpose in the frame 1. The platen is operated by a connecting rod 3 pivoted on a crank 4 on the shaft 5 which is driven by gear-wheels 6 and 7. The connecting rod 3 is also pivotally connected to a shaft 8 mounted in the platen 2. An eccentric sleeve 9 is provided on the shaft 8 and is embraced by the head 10 of the connecting rod 3, so that by rotating said shaft 8 the platen 2 may be adjusted to vary the pressure exerted by the same. To readily adjust the platen an arm 12 is rigidly mounted on the shaft 8 so that by the movement of the

said arm 12 the shaft 8 is rotated. The aforesaid parts are duplicated upon the opposite side of the press and the said arm 12 is connected with the corresponding arm on the opposite side of the press by an adjuster-bar 13.

Upon the platen 2 is a rack 14, into the teeth of which rack fits a projecting lug 15 on the adjuster-plate 16, which latter may be set and bolted in any desired position upon the rack 14. The said adjuster-plate 16 is provided with a recess 17 into which fits the end of a latch-bolt 18, mounted in bearings 19 and 20 on the adjuster-bar 13, thus holding the adjuster-bar and the shaft 8 in a fixed position. By withdrawing the latch-bolts the adjuster-bar 13 and the shaft 8 may be adjusted.

The latch-bolt, as shown in Fig. 4, is provided with a spring 22 to depress the same and hold it in engagement with the adjuster-plate 16. To withdraw the latch-bolt, a lever 24 is provided, which latter has the latch-bolt 18 pivoted therein at the point 25. The lever 24 rests upon the top of the bearing 19 on the adjuster-bar and when the lever 24 is turned in either direction the lever will bear against the bearing 19 as a fulcrum and raise the latch-bolt 18 against the action of the spring 22. The latch-bolts are duplicated and are located at either side of the press. The levers 24 are connected by a handle 30 so that both latch-bolts may be raised simultaneously by the operation of the said handle.

The lever 24 is provided with a boss 26 which is formed at right angles with the lower portion of the lever. The said boss is provided with a screw-threaded aperture 27 so that the handle 30 may be secured to the boss 26 by the bolt 31. The lower portion of the lever is bifurcated to receive the end of the latch-bolt 18 which is pivotally connected to the lever by the pin 28.

The handle 30 is made as shown in Figs. 2 and 3 and may readily be attached to the levers 24 when the latter are constructed in the manner above described. The handle is originally made with the press and used to move the platen. It will readily be seen that by my improved lever the handle can be utilized by attaching it to the latch operating device thus saving the labor and expense of making a handle especially for the latch operating attachment.

Having thus described my invention I claim and desire to secure by Letters Patent:—

In a printing press comprising a platen, 5 an adjusting shaft, arms on said shaft and an adjuster-bar extending between said arms, the combination of bearings on said adjuster-bar, a latch-bolt in each of said bearings, a spring on said latch-bolt, a lever 10 pivoted to said latch-bolt, said lever having a boss formed thereon at right-angles to the lower portion of said lever, a screw-threaded aperture formed in said boss, a handle ex-

tending between said bearings, said handle having apertures formed in the ends of the same and bolts adapted to pass through the apertures formed in the ends of said handle and enter the screw-threaded apertures in the said bosses on the said levers. 15

In testimony whereof I affix my signature 20 in presence of two witnesses.

FREDERICK E. MEEHAN.
